UNITED STATES PATENT OFFICE

JAFEW S. VAN BUREN, OF ALBANY, NEW YORK, ASSIGNOR TO RATHBONE, SARD & COMPANY,
OF ALBANY, NEW YORK, A CORPORATION OF NEW YORK.

DESIGN FOR A COOKING-STOVE.

No. 39,652.

Specification for Design.

Patented Oct. 27, 1908.

Application filed August 20, 1908. Serial No. 449,576. Term of patent 8½ years.

To all whom it may concern:

Be it known that I, JAFEW S. VAN BUREN, a citizen of the United States, residing at Albany, in the county of Albany and State of New York, have invented a new, original, and ornamental Design for Cooking-Stoves, of which the following is a specification, reference being had to the accompanying drawing, forming a part thereof.

The figure is a perspective view of a cooking stove showing my new design.

I claim:

The ornamental design for a cooking stove, as shown.
